UNITED STATES PATENT OFFICE.

RUFUS K. HELPHENSTINE AND JAMES E. MCKAHAN, OF WASHINGTON,
DISTRICT OF COLUMBIA.

DESIGN FOR A BOTTLE.

SPECIFICATION forming part of Design No. 21,244, dated December 15, 1891.

Application filed September 29, 1891. Serial No. 407,195. Term of patent 7 years.

To all whom it may concern:

Be it known that we, RUFUS K. HELPHENSTINE and JAMES E. MCKAHAN, citizens of the United States, residing at Washington, in the District of Columbia, have invented and produced a new and original Design for Bottles, of which the following is a specification, reference being had to the accompanying drawings, showing a part hereof.

10 Figure 1 is a perspective view of a bottle, showing our design; and Fig. 2 is a vertical sectional view of the same.

The leading feature of our design for bottles consists of a base, a vertical monument 15 or shaft rising centrally from the base, and stars on the base around the lower end of the shaft.

A designates the base, which is semi-spherical in outline. The base is made flat on the 20 under side, and the inside thereof is hollow.

B is the representation in minature of the shaft known as the "Washington Monument,"

which is tapering in form, substantially square in cross-section, with a pyrimidal cap b, and hollow. This hollow shaft rises centrally from the curved surface of the base A, and the lower end of said hollow shaft opens into and through the hollow interior of the base.

On the upper side of the base and extending in series around the central monument or 30 shaft are the stars D, which may be either raised above the surface of the base or *in intaglio*.

What we claim as new is—

The design for a bottle herein shown and 35 described.

In testimony that we claim the foregoing we hereunto set our hands in the presence of two witnesses.

R. K. HELPHENSTINE.
J. E. MCKAHAN.
